THREAD CUTTING AND NIPPING DEVICE FOR SEWING MACHINES

Arthur N. Hale, Stratford, Conn., assignor to The
Singer Manufacturing Company, Elizabeth,
N. J., a corporation of New Jersey

Application October 14, 1939, Serial No. 299,455

12 Claims. (Cl. 112—252)

This invention relates to thread-severing devices for sewing machines and has for its primary object to provide simple means for quickly and easily severing the sewing thread extending from the under face of the work to the thread-supply.

Another object of the invention is to provide improved means for severing the sewing thread extending from the under face of the work, without inverting the work. A still further object of the invention is to provide a sewing machine with simple means for severing the thread extending from the under face of the work while the work is disposed upon the sewing machine work-support and for nipping the end of the severed thread extending to the lower thread-supply.

The invention has also for its object to provide a sewing machine work-support, and more particularly the work-arm type of work-support, with means disposed above said work-support for severing and nipping a severed end of thread extending from the under face of the work, which thread-severing and nipping means is constructed and arranged so as not to obstruct manipulation of the work incidental to stitching the same.

With these and other objects in view, as will hereinafter appear, the invention consists in the thread-severing and nipping device described in connection with the accompanying drawing which illustrates a preferred embodiment of the invention and in which:

Fig. 1 represents a perspective view of the free end portion of a sewing machine work-arm provided with the improved thread-severing and nipping device, and showing the sewing machine needle and presser-foot. Fig. 2 is an enlarged top plan view of the thread-severing and nipping device detached from the machine. Fig. 3 represents an enlarged longitudinal section of the thread-severing and nipping device, the portion of the work-arm supporting said device being shown in section. Fig. 4 is an enlarged front end elevation of the thread-severing and nipping device.

The present improvement has been applied to a sewing machine which is particularly adapted for darning and embroidering, which sewing machine is in part shown in the drawing as having a horizontally disposed work-arm 1 provided with a cylindrical end-cap 2 having an openable end-closure plate 3. The end-cap 2 houses a looper-taker mechanism of any usual or suitable construction (not shown) and complementary to the vertically reciprocatory thread-carrying needle 4 in the formation of lock-stitches, said end-cap having the usual needle-aperture 5. However,

the present invention is not limited to any particular form of stitch-forming mechanism, as it will be obvious from the following description that there may be employed a thread-carrying chain-stitch looper for cooperation with the thread-carrying needle, or some other suitable or desired form of stitch-forming mechanism. Opposed to the work-support is a presser-foot 6 of any usual or suitable construction.

Secured by screws 7 upon the cylindrical end-cap 2 rearwardly and in the region of the needle-aperture 5 therein, is the flat shank of a thin knife-blade 8 having a narrow end portion thereof, which preferably extends lengthwise of the work-arm 1, bent away from said work-arm to provide an outwardly directed cutting edge 8' which is preferably spaced slightly from said work-arm.

Overlying the knife-blade 8 and secured by the screws 7 upon the work-arm end-cap 2, is the rearward end of a guard-plate 9. The guard-plate 9 has an outwardly bowed portion between its ends formed with substantially parallel thread-receiving slots 10 providing a plurality of laterally spaced knife-guarding ribs 11 overlying the cutting-edge 8' of the knife-blade 8, said ribs 11 preferably extending crosswise of said cutting edge and circumferentially of the end-cap 2.

The forward end portion 12 of the guard-plate 9 is depressed into a slot 13, provided in the end-cap 2, so as to be substantially flush with the inner face of said end-cap. Extending upwardly from opposite sides of the front end portion 12 of the guard-plate, within and directly adjacent the ends of the slot 13, are divergent ears 14 having inwardly or reversely bent free ends, thereby providing clips. Inserted into the clips 14 are the opposite end coils of a helical spring 15 which is held bowed outwardly between its ends by said clips, whereby adjacent coils at the upper side of the spring are spread apart to facilitate receiving a thread, and are compressed toward the lower side of the spring to nip the thread. The opposite longitudinal edges of the end-cap slot 13 confine the spring 15 against escape from the clips 14.

When it is desired to sever the sewing thread *a* extending from the under face of the work to the end-cap needle-aperture 5, the work is merely slid rearwardly upon and generally circumferentially of the end-cap 2, thereby drawing the thread *a* between any two coils of the spring 15 and into a thread-receiving slot 10 between the guard ribs 11. The thread *a* is thereby brought

into engagement with the cutting edge 8' of the blade 8 and is severed by said blade. While the thread-nipping action of the spring 15 is such as to assist in severing the thread by retarding rearward movement of the thread, the severed end of the thread retained by the spring 15 is readily withdrawn therefrom in the succeeding stitching operation.

The simple construction of the thread-severing and nipping device described lends itself to its employment in a darning machine having a work-arm of small compass, without obstructing manipulation of the work. Furthermore, the device provides for severing the under thread whenever desired, without removing the work from the work-support or inverting the work, as well as for temporarily holding the severed end of the thread leading to the under thread supply. These features are of particular advantage when darning tubular work, in that it obviates the necessity of turning the work inside out in order to sever the under thread, in the absence of some more elaborate and therefore complicated mechanically operated thread-cutter.

Having thus set forth the nature of the invention what I claim herein is:

1. A thread-severing device for a sewing machine having a work-support provided with a needle-aperture, and stitch-forming mechanism including a reciprocatory needle, said device comprising a knife-blade secured upon and having a cutting edge directed outwardly away from said work-support, laterally spaced guard-elements extending crosswise of and overlying said cutting edge, and thread-nipping means disposed upon said work-support between said knife-blade and said needle-aperture.

2. A thread-severing device for a sewing machine having a work-support provided with a needle-aperture, and stitch-forming mechanism including a reciprocatory needle, said device comprising a knife-blade secured upon and having a cutting edge directed outwardly away from said work-support, a guard-plate secured upon said work-support and having an outwardly bowed portion thereof overlying said cutting edge, said outwardly bowed portion of the guard-plate being provided with a plurality of laterally spaced guard-ribs and intervening thread-receiving slots extending crosswise of said cutting edge, and thread-nipping means disposed upon said work-support between said knife-blade and said needle-aperture.

3. A thread-severing device for a sewing machine having a work-support provided with a needle-aperture, and stitch-forming mechanism including a reciprocatory needle, said device comprising a knife-blade secured upon and having a cutting edge directed outwardly away from said work-support, a guard-plate secured upon said work-support and having an outwardly bowed portion thereof overlying said cutting edge, said outwardly bowed portion of the guard-plate being provided with laterally spaced guard-ribs and intervening thread-receiving slots extending crosswise of said cutting edge, and thread-nipping means sustained by said guard-plate in advance of said knife-blade.

4. A thread-severing device for a sewing machine having a work-support provided with a needle-aperture, and stitch-forming mechanism including a reciprocatory needle, said device comprising a knife-blade secured upon and having a cutting edge directed outwardly away from said work-support, a guard-plate secured upon

5 said work-support and having an outwardly bowed portion thereof overlying said cutting edge, said outwardly bowed portion of the guard-plate being provided with laterally spaced guard-ribs and intervening thread-receiving slots extending crosswise of said cutting edge, and thread-nipping means comprising a coil-spring sustained by said guard-plate in advance of said knife-blade.

5. A thread-severing device for a sewing machine having a work-support provided with a needle-aperture, and stitch-forming mechanism including a reciprocatory needle, said device comprising a knife-blade secured upon and having a cutting edge directed outwardly away from said work-support, laterally spaced guard-ribs extending crosswise of and overlying said cutting edge, and thread-nipping means comprising a coil-spring bowed outwardly between its ends and disposed upon said work-support in advance of said knife-blade.

20 6. A thread-severing device for a sewing machine having a work-support provided with a needle-aperture, and stitch-forming mechanism including a reciprocatory needle, said device comprising a knife-blade secured upon and having a cutting edge directed outwardly away from said work-support, a guard-plate secured upon said work-support and having an outwardly bowed portion thereof overhanging said cutting edge, said outwardly bowed portion of the guard-plate being provided with a plurality of laterally spaced guard-ribs and intervening thread-receiving slots extending crosswise of said cutting edge, and thread-nipping means comprising a coil-spring sustained by said guard-plate in advance of said knife-blade, said coil-spring being bowed outwardly between its ends to open the upper portions of the coils thereof and to compress the lower portions of said coils.

35 7. A thread-severing device for a sewing machine having a work-support provided with a needle-aperture and stitch-forming mechanism including a reciprocatory needle, said device comprising a knife-blade secured upon and having a cutting edge directed outwardly away from said work-support, a slotted knife-guard overlying said cutting edge and provided in advance of said cutting edge with clips spaced laterally of said knife-guard, and a thread-nipping coil-spring sustained by said clips in advance of the cutting edge of said knife-blade.

40 8. A thread-severing device for a sewing machine having a work-support provided with a needle-aperture and stitch-forming mechanism including a reciprocatory needle, said device comprising a knife-blade secured upon and having a cutting edge directed outwardly away from said work-support, said work-support having a slot in advance of and lengthwise substantially parallel to the cutting edge of said knife-blade, a slotted knife-guard secured at its rearward end upon said work-support to overlie said cutting edge and having a depressed forward end portion disposed in said slot of the work-support, divergent ears rising from opposite sides of said knife-guard within said slot, and a thread-nipping coil-spring sustained at its opposite ends by said ears and bowed outwardly between its ends.

45 9. A sewing machine having a reciprocatory needle, a work-arm free at one end thereof and lengthwise disposed substantially normal to the path of needle-reciprocation, said work-arm being provided with a needle-aperture, a knife-blade disposed upon said work-arm rearwardly and below the level of said needle-aperture, said

knife-blade having its cutting edge extending substantially lengthwise and directed outwardly away from the work-supporting face of said work-arm, and laterally spaced guard-ribs overlying the cutting edge of said knife-blade and lengthwise extending substantially circumferentially of said work-arm.

10. A sewing machine having a reciprocatory needle, a work-arm free at one end thereof and lengthwise disposed substantially normal to the path of needle-reciprocation, said work-arm being provided with a needle-aperture, a knife-blade disposed upon said work-arm rearwardly of said needle-aperture, laterally spaced guard-ribs overlying and extending crosswise of the cutting edge of said knife-blade, and thread-nipping means disposed upon said work-arm between said needle-aperture and said knife-blade.

11. A sewing machine having a vertically reciprocatory needle, a work-support provided with 20

a needle-aperture and with a slot in the work-supporting face thereof in the region of said needle-aperture, and an under-thread nipping device comprising a coil-spring having its opposite ends anchored in said slot and bowed outwardly between its ends to protrude above the work-supporting face of said work-support.

12. A knife guarding and thread-nipping device for use in connection with sewing machines, comprising a knife-guard plate formed between its ends with an arched portion having laterally spaced knife-guarding ribs and an intervening thread-receiving slot, said guard-plate being provided at one end thereof with laterally spaced and divergent ears upturned from the side edges of said plate at the arched side thereof, and a thread-nipping coil spring supported at its opposite ends by said ears and bowed outwardly between its ends.
